(57) **CLAIM**

The ornamental design for an automobile tire, as shown and described.

DESCRIPTION

FIG. 1 is a front view of the automobile tire;

FIG. 2 is a rear view of the automobile tire;

FIG. 3 is a left-side view of the automobile tire;

FIG. 4 is a top view of the automobile tire;

FIG. 5 is a perspective view of the automobile tire;

FIG. 6 is an enlarged view of X1—X2 in the front view of the automobile tire; and,

FIG. 7 is an enlarged cross-section view taken along the line A1—A2 in a space between two broken lines of Part B of FIG. 6.

The broken lines are for illustrative purposes only and form no part of the claimed design.

The right-side view is the same as the left-side view and the bottom view is the same as the top view.
